CHAIN CUTTER FOR MACHINES FOR
SEWING LOOPED FABRICS

Ritchie F. Ball, Narrows, Va.

Application October 14, 1932, Serial No. 637,823
Renewed September 25, 1933

7 Claims. (Cl. 112—252)

This invention relates to a cutter attachment for a looping machine designed for joining knitted fabric in the form of stockings and like articles, wherein said stockings when acted on by the looping machine are joined by a chain thread and the present invention has for the primary object, the provision of means to automatically sever the chain thread between the stockings on the completion thereof by the looper so that the completed stockings may be individually removed and obviate the customary practice of cutting the chain thread manually by the use of scissors or similar hand tools.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a fragmentary plan view illustrating a looping machine with a cutter attachment applied thereto and constructed in accordance with my invention.

Figure 2 is a fragmentary side elevation illustrating the attachment in the act of severing the chain thread between stockings.

Figure 3 is a detail view partly in section illustrating the mounting and adjustment of the cutter attachment.

Figure 4 is a plan view illustrating a knife holder.

Figure 5 is a sectional view taken on the line 5—5 of Figure 3.

Figure 6 is a sectional view taken on the line 6—6 of Figure 3.

Referring in detail to the drawings, the numeral 1 indicates in its entirety a conventional type of looping machine designed especially for joining parts of unfinished knitted stockings and like articles, and includes the usual disc 2 supported by the arm 3 and rotated by a drive shaft 4. The drive shaft and operating means therefor and the arm 3 are supported by a head 5, the disc 2 being provided with the usual radially extending impaling pins 6 on which the knitted fabric is mounted. As this type of looping machine is well known in the art it is not thought necessary to herein describe the operation of the same other than that the stockings and like articles are joined to each other by a chain thread 7, which must be severed on the removal of the completed stockings from the machine and to automatically accomplish this, my invention is applied to the looping machine and consists of a knife supporting plate 8

apertured, as shown at 9, to rotatably receive the drive shaft 4 and is limited in its endwise movement on the shaft by a coiled spring 10 surrounding the shaft with one end bearing against a collar 11 fixed to the shaft and its other end bearing against the knife supporting plate and forcing the latter against a hub 12 fixed to the drive shaft and carrying a chain pick-up hook 13. The hook 13 is adapted to rotate with the drive shaft while the knife plate remains stationary and as the stockings are completed on the looping machine the hook engages under the chain thread between each pair of stockings and draws the thread upwardly into engagement with a knife blade 14 carried by the plate 8 so that the stockings are separated from each other to permit their removal from the looping machine. The knife blade 14 is adjustably secured to the plate 8 by set bolts 15 and the plate 8 has extending therefrom a substantially L-shaped arm 16 carrying at its free end an adjustable bolt 17 adapted to engage with the disc supporting arm 3 of the looping machine to prevent rotation of the knife blade 14 with the shaft 4. The set bolt 17 being adjustably connected to the arm 16 permits the location of the knife relative to the hook 13 to be varied.

While I have shown and described the preferred embodiment of my invention, it will be understood that minor changes in construction, combination and arrangement of parts may be made without departing from the spirit and scope of my invention, as claimed.

Having described the invention, I claim:

1. In combination with a looping machine having a rotatable disc supported by an arm and provided with impaling pins and a drive shaft to impart rotation to said disc, a knife supported by the shaft and arm and means on the shaft to bring a chain thread connecting knitted articles on the impaling pins into engagement with the knife for automatically severing said chain thread during the rotation of the shaft.

2. In combination with a looping machine having a rotatable disc supported by an arm and provided with impaling pins and a drive shaft to impart rotation to said disc, a knife supported by the shaft and arm and means on the shaft to bring a chain thread connecting knitted articles on the impaling pins into engagement with the knife for automatically severing said chain thread during the rotation of the shaft, and means for adjusting the knife relative to said means.

3. In combination with a looping machine having a rotatable disc supported by an arm and

- provided with impaling pins and a drive shaft to impart rotation to said disc, a knife plate apertured to receive the shaft, means engaging said arm to hold the plate against rotation with the shaft, a knife carried by the plate and means on the shaft to bring a chain thread connecting knitted articles on the impaling pins into engagement with the knife for automatically severing said chain thread during the rotation of the shaft.

4. In combination with a looping machine having a rotatable disc supported by an arm and provided with impaling pins and a drive shaft to impart rotation to said disc, a knife plate apertured to receive the shaft, means engaging said arm to hold the plate against rotation on the shaft, a knife adjustably mounted on the plate and means on the shaft to bring a chain thread connecting knitted articles on the impaling pins into engagement with the knife for automatically severing said chain thread during the rotation of the shaft.

5. In combination with a looping machine having a rotatable disc supported by an arm and provided with impaling pins and a drive shaft to impart rotation to said disc, a knife plate apertured to receive the shaft, means engaging said arm to hold the plate against rotation on the shaft, a knife adjustably mounted on the plate, a hook-shaped element fixed to the shaft for engaging a chain thread connecting knitted articles on the impaling pins and bringing said chain thread into engagement with the knife for automatically severing said thread during the rotation of said shaft.

6. In combination with a looping machine having a rotatable disc supported by an arm and provided with impaling pins and a drive shaft to impart rotation to said disc, a plate apertured to receive the shaft, a knife blade adjustably secured to the plate, a hub secured to the shaft and engaging one side of the plate, a spring on the shaft and engaging the other side of the plate, a collar fixed to the shaft and engaging the other end of the spring, a hook carried by the hub to engage and bring a chain thread connecting knitted articles on the impaling pins into engagement with the knife blade for automatically severing said chain thread during the rotation of the shaft, and means engaging the arm to prevent rotation of the plate with the shaft.

7. In combination with a looping machine having a rotatable disc supported by an arm and provided with impaling pins and a drive shaft to impart rotation to said disc, a plate apertured to receive the shaft, a knife blade adjustably secured to the plate, a hub secured to the shaft and engaging one side of the plate, a spring on the shaft and engaging the other side of the plate, a collar fixed to the shaft and engaging the other end of the spring, a hook carried by the hub to engage and bring a chain thread connecting knitted articles on the impaling pins into engagement with the knife blade for automatically severing said chain thread during the rotation of the shaft, an L-shaped arm carried by the plate, and adjustable means between the L-shaped arm and the first-named arm to adjust the knife blade relative to the hook.
